UNITED STATES PATENT OFFICE.

EDWARD F. TALLEY, OF WEBB CITY, MISSOURI, ASSIGNOR OF ONE-HALF TO RALPH S. KELLEY, OF WEBB CITY, MISSOURI.

CHECK AND CHECK-BOOK PROTECTOR.

1,159,617.

Specification of Letters Patent.

Patented Nov. 9, 1915.

Application filed May 1, 1915. Serial No. 25,205.

To all whom it may concern:

Be it known that I, EDWARD F. TALLEY, a citizen of the United States, residing at Webb City, in the county of Jasper and 5 State of Missouri, have invented certain new and useful Improvements in Check and Check-Book Protectors, of which the following is a specification.

The present invention relates to a check 10 and check book protector, and has for its object to provide a device of this character which is adapted to receive and protect a check book so that the same will not be soiled or mutilated as the result of being carried in 15 the pocket or roughly handled, and which also embodies novel features of construction whereby the check can be readily perforated or marked so as to render it impossible for any holder to surreptitiously raise the 20 amount thereof.

Further objects of the invention are to provide a device of this character which is comparatively simple and inexpensive in its construction, which can be readily carried in 25 the pocket, which can be made to fit any size of check book, and which provides a simple and dependable means for quickly marking the check in such a manner that the amount for which the check is made payable cannot 30 be subsequently raised by some unscrupulous holder.

With these and other objects in view the invention consists in certain combinations and arrangements of the parts as will more 35 fully appear as the description proceeds the novel features thereof being pointed out in the appended claims.

For a full understanding of the invention, reference is to be had to the following 40 description and accompanying drawings, in which:

Figure 1 is a plan view of a check and check book protector constructed in accordance with the invention, a check being shown 45 in the position initially assumed when being perforated to prevent the raising thereof. Fig. 2 is a longitudinal sectional view on the line 2—2 of Fig. 1, a check book being shown by dotted lines, and the check being re- 50 moved from under the perforated plate.

Fig. 3 is an enlarged transverse sectional view on the line 3—3 of Fig. 1.

For a full understanding of the invention, reference is to be had to the following description and accompanying drawing in 55 which corresponding and like parts are indicated by like reference characters.

Specifically describing the present embodiment of the invention, the numeral 1 designates the back of the check book holder and 60 protector, said back being substantially U shaped in cross section and being adapted to receive and fit snugly over the stub end of a check book. Cover plates 2 are hinged at 3 to the edges of the back 1 and are slightly 65 larger than the covers of the check book to be received, said back and cover plates being formed of any suitable material such as sheet metal or aluminum. Each of the cover plates 2 is provided with a pocket for the 70 reception of one of the covers of the check book, and these pockets may be conveniently formed by means of plates 4 which are spaced from the inner faces of the cover plates 2 and carried thereby. The sides and outer 75 ends of the plates 4 are shown as offset at 4^a and engaged by the returned edges 2^a of the cover plates 2, although the exact manner of connecting the plates is immaterial and any suitable construction may be employed. The pockets formed between the plates 2 and 4 open toward the back 1 and receive the covers of the check book so as to retain the check book in proper position within the protector. In Fig. 2 a check book 85 A is indicated by dotted lines as in position within the holder or protector. When the cover plates 2 are both swung back as far as they will go the check book A can be readily placed in position within the holder 90 or removed therefrom, although when the cover plates 2 are closed or only partially opened the check book is retained securely in position.

The check perforator or marker includes a 95 slightly resilient plate 5 which is applied to the outer face of one of the cover plates 2 and secured at one of its edges to the cover plate by suitable fastening means such as the rivets 6. In the present instance the edge of 100

the perforator plate 5 remote from the hinge joint 3 is secured to the cover plate 2 by the rivets 6, and the perforator plate is arranged upon the cover plate in such a manner as not to interfere with the swinging movement of the cover plate. The perforator plate 5 is stamped or cut in such a manner as to provide a series of longitudinally extending spring tongues 7 which are preferably arranged in a number of groups, the tongues of each group being in transverse alignment with each other, while the corresponding tongues of the different groups are in longitudinal alignment. The spring tongues 7 are each free on three sides and attached to the plate 5 at the fourth side so that they can be readily flexed outwardly a sufficient amount to admit of a check being placed thereunder. It will also be observed that the alternate tongues 7 in the transverse rows extend longitudinally in opposite directions, and that an open space 8 is provided at one side of each of the spring tongues. The perforator plate 5 is also cut to provide a comparatively long spring tongue 9 which has an open space 10 at one end thereof. Such a construction admits of a compact arrangement of the spring tongues 7, and at the same time enables the check to be quickly and accurately positioned under the various spring tongues so as to perforate the desired number therein.

Each of the spring tongues 7 is provided with rearwardly projecting prongs 11 which are arranged on the outline of a number or character. These prongs 11 may be conveniently formed by punching the perforator plate 5, as indicated upon the drawing, and the following numbers and characters are formed upon the different tongues: "\$", "1", "2", "3", "4", "5", "6", "7", "8", "9", and "+". It will also be observed that the tongue 9 has the words "Not over" outlined thereon by the prongs 11, and that correspondingly arranged depressions 12 are provided on the cover plate 2 to receive the prongs 11 and coöperate therewith to perforate a piece of paper such as a check which may be inserted between the perforator plate 5 and the cover plate 2.

After a check B has been properly made out in the usual manner it is detached from the check book and inserted between the perforator plate 5 and the cover plate 2, as indicated by Fig. 1. It is first manipulated to bring the upper left hand edge thereof under the opening 10 at the end of the long tongue 9, thereby bringing the check in position to have the words "Not over" perforated therein. Care is exercised to get the check accurately in position so that it extends transversely across the cover plate, and the tongue 9 is then forcibly pressed inwardly

by the fingers or struck lightly with some blunt instrument so that the prongs 11 projecting from the back thereof perforate the words "Not over" in the check. The check B is next manipulated until the last letter of the word "Over" previously perforated therein shows through the space 8 at the side of the spring tongue provided for making the dollar mark. After the check has again been accurately positioned the spring tongue 7 is forced inwardly to perforate the dollar mark in the check. This operation is repeated for the successive numbers necessary to indicate the highest amount for which the check should be cashed by the bank, and one or more of the cross marks may then be perforated in the check to prevent the possibility of additional figures being added to the number previously perforated. The cover plate 2 serves as a backing or base plate for the perforator plate 5, and after the check has been made out and detached from the check book, the highest amount in dollars for which it is payable can be quickly and easily marked thereon by perforations so that there will be no danger of the check being raised before presentation at the bank for payment.

Having thus described the invention, what I claim as new and desire to secure by Letters Patent is:

1. A check book protector, including a base plate, a resilient perforator plate carried by the base plate and superposed over the same to admit of a check being manipulated between the base plate and perforator plate, said perforator plate being cut and having portions thereof removed to provide a series of spaced and parallel bars extending transversely across the same and provided with laterally projecting resilient tongues, the tongues being arranged in rows between the bars and having view openings between the same, and prongs projecting rearwardly from the different tongues and arranged to outline various characters so that by successively positioning the check under the different tongues and forcibly pressing the tongues toward the base plate the characters can be punched into the paper, the view openings between the tongues admitting of the check being accurately positioned under each of the tongues.

2. A check protector, including a base plate, a perforator plate carried by the base plate and superposed upon the same so that a check can be manipulated between the base plate and perforator plate, the perforator plate having portions thereof removed to provide a series of parallel and spaced transverse bars provided with laterally projecting resilient tongues, the tongues of each bar projecting alternately from opposite sides

thereof and being received between the tongues of adjacent bars so that the tongues are arranged in transverse rows between the parallel bars, and prongs projecting rearwardly from the different tongues and arranged to outline various characters, so that by successively placing the check under the different tongues and forcibly pressing the

same toward the base plate the characters can be punched into the paper. 10

In testimony whereof I affix my signature in presence of two witnesses.

EDWARD F. TALLEY.
